US00D659596S

(12) **United States Design Patent**
Zhang et al.

(10) **Patent No.:** US D659,596 S
(45) **Date of Patent:** ** May 15, 2012

(54) **FRAME OF ELECTRIC VEHICLE**

(75) Inventors: **Xue-qing Zhang**, SuZhou (CN); **Xue Li**, SuZhou (CN)

(73) Assignee: **Suzhou Eagle Electric Vehicle Manufacturing Co., Ltd.**, Suzhou, Jiangsu Province (CN)

(**) Term: **14 Years**

(21) Appl. No.: **29/393,994**

(22) Filed: **Jun. 10, 2011**

(30) **Foreign Application Priority Data**

Jan. 31, 2011 (CN) 2011 3 0019399

(51) **LOC (9) Cl.** **12-11**

(52) **U.S. Cl.** **D12/110**

(58) **Field of Classification Search** D12/110, D12/107; 180/219, 220, 225, 228, 231, 311, 180/312, 230, 218, 65.1, 65.5-65.8, 68.1, 180/68.2, 68.5; 280/274-280, 281.1, 283-288, 280/288.1-288.3
